Attorney

UNITED STATES PATENT OFFICE.

GEORGE T. BLOOMINGDALE, OF PARKERSBURG, WEST VIRGINIA.

WINDOW-CLEANING DEVICE.

1,385,603.

Specification of Letters Patent. Patented July 26, 1921.

Application filed April 2, 1921. Serial No. 458,134.

To all whom it may concern:

Be it known that I, GEORGE T. BLOOMINGDALE, a citizen of the United States, residing at Parkersburg, in the county of Wood 5 and State of West Virginia, have invented certain new and useful Improvements in Window-Cleaning Devices, of which the following is a specification, reference being had to the accompanying drawings.

10. This invention relates to certain improvements in window cleaning devices, and it is an object of the invention to provide a structure of this general character having novel and improved means whereby the pane may 15 be conveniently and effectively wiped when the occasions of practice may so necessitate.

Another object of the invention is to provide a novel and improved device of this 20 general character wherein the stiles are slotted, with carriages riding within the slots, and said carriages being connected by wiping elements for contact with the opposed faces of the window pane.

An additional object of the invention is 25 to provide a novel and improved device of this general character including slotted stiles in each of which is slidably arranged a carriage for a wiping element and wherein means are provided for closing said slot 30 when the carriage is substantially at the limit of its movement in one direction.

The invention consists in the details of 35 construction and in the combination and arrangement of the several parts of my improved window cleaning device whereby certain important advantages are attained and the device rendered simpler, less expensive and otherwise more convenient and advantageous for use, as will be hereinafter 40 more fully set forth.

The novel features of my invention will hereinafter be definitely claimed.

In order that my invention may be the 45 better understood, I will now proceed to describe the same with reference to the accompanying drawings, wherein:

Figure 1 is a view in elevation, with portions broken away, of a window cleaning device arranged in accordance with an embodiment of my invention;

Fig. 2 is an enlarged fragmentary sectional view taken through a side marginal portion of the device as illustrated in Fig. 1;

Fig. 3 is an enlarged fragmentary sectional view taken through the upper portion of the structure illustrated in Fig. 1;

Fig. 4 is an enlarged fragmentary vertical sectional view taken through the upper portion of the device and illustrating the wiping elements; and

Fig. 5 is a fragmentary view in elevation of an end portion of the tubular member comprised in a wiping element.

As disclosed in the accompanying drawings, R denotes the upper rail of the window 65 structure and R' the lower rail. The opposite end portions of these rails R and R' are connected by the stiles S. Each of the stiles S comprises a pair of transversely spaced strips 1. Overlying the outer edges 70 of the strips 1 of each stile S and secured therewith, as at 2, by screws or the like is a metallic plate 4, said plate bridging the space between the strips 1. The opposite ends of the metallic strip 4 are provided with the right angular extensions 5 overlapping the outer edges of the rails R and R' and suitably secured thereto by the screws 6 or the like. By this means, a rigid and strong sash frame is provided.

The rails R and R' are also connected by the supplemental stiles S' positioned in close proximity to but slightly spaced from the inner margin of the main stiles S whereby the side portions of the sash structure 85 are provided with the vertically directed slots 7 extending the entire distance between the rails R and R'.

The marginal face or edge of each of the supplemental stiles S' opposed to the adjacent stile S at its transverse center is provided therewith with a groove or channel 8 herein disclosed as V-shaped in cross section while the opposed longitudinal edge or face of said stile S' is provided with a 90 groove or rabbet 9 to receive the marginal portion of a window pane P.

Coacting with each pair of stiles S and S' is a carriage C. This carriage is preferably of metal and is substantially U- 100 shaped in cross section with its intermediate portion or base portion 10 arranged within a slot 7 and with its side members or wings 11 overlying the side faces of the supplemental stile S'.

Secured to the outer face of each of the

side members or wings 11 is an inwardly facing bracket 12, said bracket providing a mounting for one end portion of a wiping element E.

5 As herein disclosed, a wiping element E is arranged at each side of the pane P and each of the elements E comprises an elongated tubular member 14 having extending therealong a slot 15, the longitudinal margins of said slot substantially entirely therealong being defined by the outstanding flanges 16. Engaged with the opposite end portions of the tubular member 14 are the caps 17 provided with the trunnions 18 each 10 of which seats within a bracket 12. The trunnion 18 and the coacting socket 18^a of a bracket 12 are angular in cross section and snugly engaged so that, when the tubular member 14 is applied, the same is maintained 15 against rotation. When the tubular member 14 is applied, the slot 15 is opposed to the pane P.

19 denotes an elongated strip of felt or kindred material of a length substantially 25 equal to the space between the inner ends of the applied caps 17. This strip 19 is folded transversely with the folded portion inserted within the tubular member 14 through the slot 15. A rod 20 is then placed within the 30 member 14 between the overlying portions of the folded strip 19, said rod 20 being of a length to extend within the applied caps 17 whereby said rod 20 serves to maintain effectually the strip in applied position. This 35 strip 19 is of such width that when it is folded and applied within the tubular member 14, the free longitudinal marginal portions thereof will extend exteriorly of the member 14 a distance sufficient to have contact 40 with the adjacent face of the pane P. By flexing the flanges 16, the contacting pressure of the longitudinal marginal portions of the strip 19 upon the pane P may be regulated as the necessities of practice may 45 prefer.

When the wiping elements E are in applied position, both of such elements, together with the carriages C, constitute a unitary structure adapted to be moved 50 lengthwise of the stiles S and S', the base or intermediate portions 10 of the carriages traveling along the slots 7. Normally the elements E are positioned immediately adjacent the upper rail R and by pulling downwardly thereon, the felt strips 19 or the like 55 wipe the faces of the pane P and which operation is true when the elements E are returned to their normal positions. By this means, the faces of the pane P may be maintained clean.

In order to facilitate the working of the elements E, one of the tubular members 14 is provided adjacent its opposite ends with the outstanding handles 21 riveted or otherwise securely held in applied position. Nor-

mally arranged between the strips 1 of each of the stiles S is an elongated strip 22 preferably of wood and which is of a length to extend from the bottom rail R' to a distance below the upper rail R substantially equal 70 to the vertical dimension or length of a carriage C. This strip 22 is also of a width greater than the width of the slot 7 so that said strip 22 operates to close the slot 7. The inner marginal portion of the strip 22 75 is oppositely beveled or tapered to snugly engage within the groove or channel 8 of a stile S'. The inner marginal portion of the strip 22 is normally maintained seated within the groove or channel 8 by the spring 80 members 23 coacting with the opposite end portions of the strip 22 and anchored at one end to a metallic plate 4.

When the elements E are at the limit of their upward movement or in their normal 85 positions, they are maintained therein by the carriages C resting upon the upper ends of the strips 22. These upper end portions of the strips 22 are downwardly beveled, as at 24, toward the stiles S' so that when pull 90 is imposed upon one of the tubular members 14, preferably through the instrumentality of the handles 21, the strips 22 will be forced back between the strips 1 of the stiles S so that the base or intermediate portions 10 of 95 the carriages C will readily pass along the slots 7.

My improved sash construction is particularly adapted for use in connection with a vestibule of a trolley car so that it may be 100 possible for the motorman or other train man to maintain the pane P clear. My improved sash construction, however, can be employed for other purposes, as in connection with the windows of passenger coaches 105 or the like.

From the foregoing description it is thought to be obvious that a window cleaning device embodying my invention is particularly well adapted for use by reason of 110 the convenience and facility with which it may be assembled and operated, and it will also be obvious that my invention is susceptible of some change and modification without departing from the principles and spirit 115 thereof and for this reason I do not wish to be understood as limiting myself to the precise arrangement and formation of the several parts herein shown in carrying out my invention in practice except as herein- 120 after claimed.

I claim:

1. A sash structure including stiles provided with slots extending lengthwise thereof, a carriage slidably mounted in each of the slots and including wings overlying the opposite faces of the stiles, a wiping element supported by the wings at each side of the structure, and means for normally closing each of the slots, said means coacting with 130

- the carriages for normally maintaining the same at the limit of their movement in one direction.
2. A sash structure including stiles, each 5 stile comprising a pair of transversely spaced members, a supplemental stile positioned adjacent each of the first named stiles and spaced therefrom to provide an elongated slot, an elongated strip arranged between the spaced members of each stile, 10 means for constantly urging said strip in a direction to substantially close the slot between the coacting stile and the adjacent supplemental stile, a carriage slidably engaged within each of the slots, and a wiping element connecting the carriages.
3. A sash structure including stiles, each 15 stile comprising a pair of transversely spaced members, a supplemental stile positioned adjacent each of the first named stiles and spaced therefrom to provide an elongated slot, an elongated strip arranged between the spaced members of each stile, 20 means for constantly urging said strip in a direction to substantially close the slot between the coacting stile and the adjacent supplemental stile, a carriage slidably engaged within each of the slots, and a wiping element connecting the carriages, each of 25 said strips when in its normal position co-acting with a carriage when at the limit of its movement in one direction for holding 30 said carriage against movement in an opposite direction.
4. A sash structure including stiles, each 35 stile comprising a pair of transversely spaced members, a supplemental stile positioned adjacent each of the first named stiles and spaced therefrom to provide an elongated slot, an elongated strip arranged between the spaced members of each stile, 40 means for constantly urging said strip in a direction to substantially close the slot between the coacting stile and the adjacent supplemental stile, a carriage slidably engaged within each of the slots, and a wiping element connecting the carriages, each of 45 said strips when in its normal position co-acting with a carriage when at the limit of its movement in one direction for holding 50 said carriage against movement in an opposite direction, the end portion of each of the strips adjacent the carriage when in its normal position being beveled to permit said carriage to move along the slot and by the 55 strip.

In testimony whereof I hereunto affix my signature.

GEORGE T. BLOOMINGDALE.
